UNITED STATES PATENT OFFICE.

GEORGE M. WEHRLE, OF JACKSON, CALIFORNIA.

METHOD OF JOINT SEALING.

Application filed August 9, 1926. Serial No. 128,072.

This invention relates to a method of joint sealing, and particularly to a method of sealing the joints between adjacent sections of concrete. It is well known that large concrete water tunnels, dams, etc. are poured in sections, and that upon setting and drying out the sections contract in a manner leaving a gap between the adjacent sections. In large dams, the gap is ordinarily filled with cement forced thereinto in liquid form under pressure. Various other methods are now used for sealing these gaps formed between adjacent sections of pipes and concrete tunnels.

It is the primary object of my invention to provide a novel and very useful method of sealing these gaps by the use of a flexible tube placed between the sections and expanded by cement forced thereinto under pressure and permanently held in expanded condition by the hardening of the cement.

In the accompanying drawing, I have illustrated one particular use of my invention, but it will be understood that the invention can be otherwise embodied and that the drawing is not to be construed as defining or limiting the scope of the invention, the claims appended to the specification being relied upon for that purpose.

Referring to the figures of the drawing: Fig. 1 is a fragmentary view showing one end of a concrete tunnel section illustrating the use of my invention.

Fig. 2 is an enlarged fragmentary sectional view of Fig. 1. Fig. 2 shows the same after the next adjacent section has been poured.

Fig. 4 shows the same after the concrete has set and the joint between the sections permanently sealed.

In the drawing 1 indicates the ground through which is formed a tunnel 2. Adjacent sections of concrete tunnels or pipes are illustrated at 3 or 4 as formed within the tunnel 2.

In Figs. 1 and 2, the section 3 is illustrated as poured and set. The adjacent ends of the sections are provided with overlapping joints 5 and 6.

In Fig. 3 the section 4 has been poured onto the section 3.

Fig. 4 shows the same after the section 4 has set and hardened. During this setting the concrete contracts in a manner leaving a gap, 7, between the sections. The object of

my invention herein is to provide means for permanently sealing this joint.

As illustrated in Figs. 1 and 2, I place an expansible tube 8, (preferably of rubber) sufficient thickness to prevent collapse about the end 5 of section 3 and bring the ends 9 thereof into the tunnel. The adjacent section 4 is then poured thereon over the tube in the manner shown in Fig. 3. When this section 4 has set and contracted, leaving the gap 7, 65 I force liquid cement into the tube under pressure. This pressure expands and distorts the tube as shown in Fig. 4 so that it presses tightly against both tunnel sections. I hold the tube under this pressure 70 until the cement therein has hardened. The hardened cement thereafter permanently holds the tube expanded in the sealing position.

It will be obvious from the above description and the accompanying drawing that the tube thereafter forms a permanent seal for the joint.

While the invention is herein illustrated in connection with tunnels, it will of course 80 be understood that the invention is capable of a wide application of uses other than that illustrated herein.

Having thus described my invention, what I claim and desire to secure by Letters Patent is—

1. A method of sealing joints between adjacent sections of concrete construction consisting of placing an expansible tube of sufficient thickness to prevent collapse on a poured 90 and set section along the sealing line, pouring the adjacent section thereon over the tube, permitting the sections to set and contract, and thereafter forcing liquid cement into the tube under pressure and holding the same 95 thus until the cement sets so that the hardened cement permanently holds the tube expanded in its sealing position.

2. A method of sealing joints between adjacent sections of tunnels or pipes consisting 100 of placing an expansible tube of sufficient thickness to prevent collapse on and around the end of one section, placing the other section thereon over the tube, and forcing liquid cement into the tube under pressure and holding the same thus until the cement sets so that the hardened cement permanently holds the tube expanded in its sealing position.

3. A method of sealing joints between adjacent sections of concrete tunnels or pipes 110

consisting of placing an expansible tube of sufficient thickness to prevent collapse on and around the end of a poured and set section, pouring the adjacent section thereon over the tube, permitting the sections to set and contract, and thereafter forcing the liquid cement into the tube under pressure and holding the same thus until the cement sets so that the hardened cement permanently holds the tube expanded in its sealing position.

4. A method of sealing joints between adjacent sections of concrete constructions consisting of placing a rubber tube of sufficient

thickness to prevent collapse on a poured and set section along the sealing line and extending the ends of the tube beyond the inner face of the set section, pouring the adjacent section thereon over the tube, permitting the sections to set and contract, and thereafter forcing liquid cement into the tube under pressure and holding the same thus until the cement sets so that the hardened cement permanently holds the tube expanded in its sealing position.
